UNITED STATES PATENT OFFICE.

WINFIELD L. BROOKS AND WILLIAM M. SMITH, OF WORCESTER, MASSACHUSETTS,
ASSIGNORS TO ROYAL WORCESTER CORSET COMPANY, A CORPORATION OF MASSA-
CHUSETTS.

SEWING-MACHINE ATTACHMENT FOR SPIRAL STITCHING.

Application filed October 12, 1922. Serial No. 594,140.

To all whom it may concern:

Be it known that we, WINFIELD L. BROOKS and WILLIAM M. SMITH, citizens of the United States, residing at Worcester, in the county of Worcester and State of Massachusetts, have invented or discovered certain new and useful Improvements in Sewing-Machine Attachments for Spiral Stitching, of which the following is a specification, reference being had therein to the accompanying drawings.

This invention relates to an attachment for sewing machines for effecting spiral stitching for the purpose of making an ornamental medallion or the like, the attachment preferably comprising means for guiding a filling element, as a cord or wire, between two superposed layers of fabric and the rows of spiral stitching, for the purpose of giving a ribbed appearance to the medallion and for stiffening the same so that it will hold its shape. To this end the attachment comprises an impaling pin which may be lowered upon the work which has been placed in sewing position, said pin being arranged at one side of the feed and at any desired distance from the needle. This impaling pin affords a pivot on which the work may be turned in forming the first circle of stitches. The attachment, in its preferred form, comprises a cord or wire guide carried by a pivoted arm which is adapted to be entered between two plies of fabric, and which, when the first circular row of stitches has been formed, is swung into proper position to direct a cord or wire closely adjacent to the needle of the machine and thus lay such cord or wire between two circular rows of stitches. The presser foot of the machine is provided on its bottom with two curved grooves adapted to receive the circular ribs formed by the filling cord or wire and the circular stitching, and that after one or two circular rows of stitches have been formed the impaling pin may be removed from the fabric and the work will then be fed in a spiral direction owing to the engagement of the presser foot at its curved grooves with the ribbed work, thereby feeding the work in a spiral direction in forming a medallion, the stitching commencing near the center of the medallion and extending spirally outward therefrom.

In the accompanying drawings Fig. 1 is a side view showing a portion of a sewing machine with the present invention applied thereto. Fig. 2 is a plan view of a portion of the work-plate of the machine showing the wire or cord guide and the means by which it is pivotally attached to the said work plate, and showing also the presser foot and impaling pin. Fig. 3 is a front end view of the head of the machine with the attachment applied thereto. Fig. 4 is a bottom view of the presser foot and Figs. 5 and 6 illustrate the work performed by the attachment, Fig. 6 being a somewhat diagrammatic section on line 6—6, Fig. 5.

Referring to the drawings, 12 denotes the work-plate and 13 a portion of the bracket arm of a well-known form of sewing machine. Attached to the lower portion of the head 14 of the bracket arm is a small bracket 15 in which is mounted, for vertical movement, a rod 16 to which is adjustably secured, by a set screw 17, the horizontal shank of a pointed impaling pin 18. Between the bracket 15 and a collar secured to the rod 16 is a spiral spring 17^a tending to force said rod and the impaling pin carried thereby yieldingly downward. Pivoted to the upper part of the rod 16 is a cam lever 19 by which the said rod and the impaling pin carried thereby may be lifted, when the impaling pin is not in use, as partly denoted by dotted lines in Fig. 3.

Attached to the work plate 12, as by screws 20, is a plate 21 having at its rear end a flange 22. Pivoted to the plate 21, by a screw 23, is an arm 24 carrying at its forward end a guide 25 arranged closely adjacent to the needle and adapted to direct a filling and stiffening element, as a wire 26, which is to be laid between the rows *a* of stitches to form ribs *b* in the work. The arm 24 is of thin flexible sheet metal so that it may be readily inserted between two layers or plies of fabric which are to be stitched together and between which the filling, as the wire 26, is to be guided and laid between the rows of spiral stitching. The pivoted arm 24 may be swung outward, as denoted by dotted lines in Fig. 2, when the guide carried thereby is not in use; and when in the position shown in full lines in Fig. 2

it will be held in place against inward or backward movement by a stop afforded by the flange 22 on the plate 21.

The bottom of the presser-foot 27 is constructed with two curved grooves 28 to receive the raised ribs *b* of the work and as these curved grooves 28 are mostly at one side of the feed dog *c* of the machine the work will be guided towards the left (Figs. 1 and 2) in a curved direction in forming the spiral stitching.

The operation of the invention is as follows: the two plies of layers of fabric *d* which are to receive the spiral stitching will be placed beneath the presser foot 27 of the machine in the usual manner and the impaling pin 18 will then be lowered upon the same. As the impaling pin 18 is at one side of the feed dog of the machine the action of the feed dog in advancing the work will cause the latter to be turned in a circle of which the impaling pin is the center, thereby making a circular row of stitches near the center of the medallion to be formed. When the second row of stitches is commenced the cord or wire guide may be swung into place to lay a cord or wire closely adjacent to the needle and between the first and second row of stitches, and when this second row has progressed a little distance the impaling pin may be lifted and the work will then be guided in a circular direction by the curved grooves 28 in the bottom of the presser foot 27, and the stitching will be continued in spiral form until a medallion of proper size has been formed.

By virtue of the set screw 17 engaging the horizontal shank portion of the impaling pin 18 said pin may be adjusted to different distances from the needle of the machine, according to the desired size or radius of the first circular row of stitches near the center of the medallion.

It will be noted that the grooves 28 in the bottom of the presser foot 27 are sharply curved throughout their lengths so as to have an extended curved engagement with the ribs *b* of the work, thereby ensuring a proper guiding of the work in a curved direction in forming the spiral stitching.

Having thus described our invention we claim and desire to secure by Letters Patent:

1. A sewing machine attachment for spiral stitching comprising an impaling pin on which the work may be turned, a guide adapted to direct a filling element between two plies of fabric and closely adjacent to the needle of the machine, and a presser foot having in its bottom a plurality of curved grooves.

2. A sewing machine attachment for spiral stitching comprising an impaling pin on which the work may be turned, a guide adapted to direct a filling element between two plies of fabric and closely adjacent to

the needle of the machine, and a presser foot having in its bottom a plurality of curved grooves which are located mostly at one side of the feed dog of the machine.

3. A sewing machine attachment for spiral stitching comprising an impaling pin on which the work may be turned, a guide adapted to direct a filling element between two plies of fabric and closely adjacent to the needle of the machine, and a presser foot having in its bottom a plurality of curved grooves which are located mostly at one side of the feed dog of the machine, the said guide being carried by a pivoted arm which may be swung outward away from the needle when the guide is not in use.

4. A sewing machine attachment for spiral stitching comprising a vertically movable and yieldingly mounted impaling pin on which the work may be turned, a guide adapted to direct a filling element between two plies of fabric and closely adjacent to the needle of the machine, and a presser foot having in its bottom a plurality of curved grooves.

5. A sewing machine attachment for spiral stitching comprising a vertically movable and yieldingly mounted impaling pin on which the work may be turned, a guide adapted to direct a filling element between two plies of fabric and closely adjacent to the needle of the machine, and a presser foot having in its bottom a plurality of curved grooves which are located mostly at one side of the feed dog of the machine.

6. A sewing machine attachment for spiral stitching comprising a vertically movable and yieldingly mounted impaling pin on which the work may be turned, a guide adapted to direct a filling element between two plies of fabric and closely adjacent to the needle of the machine, and a presser foot having in its bottom a plurality of curved grooves which are located mostly at one side of the feed dog of the machine, the said guide being carried by a pivoted arm which may be swung outward away from the needle when the guide is not in use.

7. A sewing machine attachment for spiral stitching comprising a vertically movable and yieldingly mounted impaling pin on which the work may be turned, a guide adapted to direct a filling element between two plies of fabric and closely adjacent to the needle of the machine, a presser foot having in its bottom a plurality of curved grooves, and means for lifting said impaling pin and holding same in raised position.

8. A sewing machine attachment for spiral stitching comprising a vertically movable and yieldingly mounted impaling pin on which the work may be turned, a

- guide adapted to direct a filling element between two plies of fabric and closely adjacent to the needle of the machine, a presser-foot having in its bottom a plurality 5 of curved grooves which are located mostly at one side of the feed dog of the machine, and means for lifting said impaling pin and holding same in raised position.
9. A sewing machine attachment for 10 spiral stitching comprising a vertically movable and yieldingly mounted impaling pin on which the work may be turned, a guide adapted to direct a filling element between two plies of fabric and closely 15 adjacent to the needle of the machine, a presser foot having in its bottom a plurality of curved grooves which are located mostly at one side of the feed dog of the machine,
- the said guide being carried by a pivoted arm which may be swung outward away 20 from the needle when the guide is not in use, and means for lifting said impaling pin and holding same in raised position.
10. A sewing machine attachment for 25 spiral stitching comprising a presser foot having in its bottom two grooves which are sharply curved throughout their lengths, and a wire or cord guide for directing a filling member between two layers of fabric to form ribs, received and guided in a circular direction by said grooves.

In testimony whereof we affix our signatures.

WINFIELD L. BROOKS.
WILLIAM M. SMITH.
